(57) **CLAIM**

The ornamental design for an earbud case, as shown and described.

DESCRIPTION

A portion of the disclosure of this patent document contains material which is subject to copyright protection. This patent document may show and/or describe matter which is or may become trade dress of iLuv Creative Technology. The copyright and trade dress iLuv Creative Technology has no objection to the facsimile reproduction by anyone of the patent disclosure as it appears in the Patent and Trademark Office patent files or records, but otherwise reserves all copyright and trade dress rights whatsoever.

FIG. 1 is a front perspective view of an earbud case according to the present invention.

FIG. 2 is a rear perspective view of the earbud case of FIG. 1.

FIG. 3 is a front view of the earbud case of FIG. 1.

FIG. 4 is a rear view of the earbud case of FIG. 1.

FIG. 5 is a left side view of the earbud case of FIG. 1.

FIG. 6 is a right side view of the earbud case of FIG. 1.

FIG. 7 is a top view of the earbud case of FIG. 1.

FIG. 8 is a bottom view of the earbud case of FIG. 1.

FIG. 9 is a front perspective view of the earbud case of FIG. 1, showing with the lid open.

FIG. 10 is a front view of the earbud case of FIG. 1, showing with the lid open; and,

FIG. 11 is a right side view of the earbud case of FIG. 1, showing with the lid open.

1 Claim, 11 Drawing Sheets
